UNITED STATES PATENT OFFICE.

CHARLES B. BUERGER, OF PHILADELPHIA, PENNSYLVANIA, ASSIGNOR TO THE ATLANTIC REFINING COMPANY, OF PHILADELPHIA, PENNSYLVANIA, A CORPORATION OF PENNSYLVANIA.

APPARATUS FOR REMOVING COKE FROM STILLS.

1,401,310.

Specification of Letters Patent.

Patented Dec. 27, 1921.

Original application filed February 7, 1918, Serial No. 215,764. Divided and this application filed March 11, 1919. Serial No. 281,914.

To all whom it may concern:

Be it known that I, CHARLES B. BUERGER, a citizen of the United States, residing in the city of Philadelphia, county of Philadelphia, and State of Pennsylvania, have invented certain new and useful Improvements in Apparatus for Removing Coke from Stills, of which the following is a specification.

10 My invention relates to apparatus for removing coke or deposit from stills employed in oil refineries for reducing or distilling petroleum or petroleum distillate or residuum.

It is the object of my invention to provide 15 apparatus which will make it possible promptly after completion of a still run, and without the loss of time incident to the cooling of the still and contents to a temperature making it possible for still cleaners

20 to enter the still as in the old and common practice, to remove the coke or practically solid deposit from the still with greater economy in time and labor, whereby the period during which the still is not in operation 25 in treating or distilling oil is materially reduced, and, consequently, the proportion of the time in which the still is in operation upon oil is materially increased.

To these ends I have provided apparatus, 30 of the character hereinafter described, in which there are employed within the still a plurality of frames, cages or pans within, around and above which the coke or the like is deposited and in which are withdrawn, 35 preferably in succession, in a horizontal direction from the still, suitably constructed for the purpose, each frame, cage or pan removing the contained and adjacent coke.

This application is a division from my 40 prior application Ser. No. 215,764, upon which issued Letters Patent No. 1,302,761.

For an illustration of one of the forms my apparatus may take, reference is to be had to the accompanying drawings, in which:

45 Figure 1 is a side elevational view, partly in section, of a still constructed and equipped in accordance with my improvements.

Fig. 2 is a horizontal sectional view, partly in plan, of a structure illustrated in Fig. 1.

50 Fig. 3 is an end elevational view of the structure of Fig. 1.

Fig. 4 is a plan view of a cage or frame.

Fig. 5 is a side elevational view of the cage or frame of Fig. 4.

Referring to the drawings, S represents 55 an oil still, here shown of the horizontal cylindrical type, suitably housed and supported by brickwork 1 forming beneath the still a firebox or combustion chamber F in which is developed the heat transmitted to 60 the still contents through the still bottom B for distillation purposes in well known manner.

A pipe 2 serves to carry off oil vapors produced during the distillation process. 65 The still may be provided if desired with the usual manholes 3, 3 at its top and the manhole 4 at one end. At one end of the still at its bottom is a manhole 5 formed by a manhole member 6 whose lower side is of 70 circular form conforming to the shape of the still bottom and whose upper side is illustrated as horizontal, Fig. 3, thereby forming a manhole of relatively great width and of a height preferably above the level 75 of the coke deposited in the still. The member 6 has the front flange 7 to which is bolted the flange 9 of the manhole cover 8.

In Figs. 4 and 5 is illustrated a cage or frame 10, rectangular in form, comprising 80 the side members 11, 11 and the diagonal member 12, all secured at opposite corners of the frame by rivets 13. And extending through the parts of the members 11 and 12 which are so held by the rivets are the holes 85 14, 14 for attachment of chains 15 or the like.

The frame illustrated is one of many forms, it being understood that any other suitable shape or form is comprehended by 90 my invention. For example, the frames may be triangular, hexagonal or any other suitable shape which will allow their placement close to each other within the still.

The frame illustrated has no bottom, and 95 this is my preferred construction, though it will be understood that my invention is not limited to bottomless frames or cages, and that pans may be employed, which latter are comprehended within the terms frame and 100 cage.

As shown in Figs. 1, 2 and 3, these frames

10 are laid upon the bottom B of the still on the inside thereof in suitable numbers practically to completely cover the still bottom. The number of frames and their size is preferably such as to allow them to lie close to the still bottom notwithstanding the buckling of the same which occurs in practice in this type of still due to the fact that the still bottom is operated at red heat. The 10 corners of the successive frames in the series are connected by chains 15 attached thereto at the holes 14 above referred to.

In the example illustrated, there are three frames per transverse row, the chain connections from one row to the next alternating on opposite sides of the still, the frames or cages being preferably so positioned that as they are successively pulled toward the left, Figs. 1 and 2, there is imparted to each in 20 succession a twisting or turning movement.

The operation is as follows:

When the cages or frames have been suitably placed within the still, the manhole 6 is closed by bolting on the cover 8. The 25 other still openings, as manholes 3 and 4, having been closed, oil to be treated is introduced into the still and operated upon in well known manner by application of heat produced in the fire chamber F.

30 During the process coke is deposited on the bottom of the still, and in it the frames 10 become embedded. As the still run approaches completion, the deposit becomes denser and denser and the final step is ordinarily to run to dryness, whereby coke or practically solid carbonaceous material lies to great depth on the still bottom. For this purpose the presence of the metallic frames 10 is of advantage in that the numerous 35 metal plates or strips of the frames readily conduct heat into the mass of coke or tar and assist in driving out all remnant oil.

When the still has been so run to dryness the run has been completed.

45 Thereupon, when necessary, steam is introduced into the still and allowed to flow for a time sufficient to displace the residual vapors and combustible atmosphere.

Immediately the manhole cover 8 is loosened it may be hoisted to the position indicated in Figs. 1 and 3 by any suitable hoisting apparatus 16 supported upon the bracket 17 carried by the still or otherwise suitably supported.

50 The chain 18, Fig. 2, is connected to the first frame 10 of the series, and connects to any suitable mechanism for exerting a pull upon the chain 18. For this purpose an ordinary power driven windlass or the like 55 may be employed. In so pulling upon the chain 18 the first frame 10 is given more or less of a twisting or turning movement, thereby loosening the coke adhering thereto or disposed within the same and the neighboring parts of the coke are separated from

the remainder of the mass and from the still bottom. This first frame is pulled out through the manhole 5 and in so moving transmits a pull through the chain 15 connecting to the second frame, which removes 70 its mass of coke; then the chain 15 connected to the first frame of the second row is brought under tension, rotating or twisting the first frame of the second row and pulling it outwardly, and so on throughout the 75 series, the frames of a row being successively pulled and more or less rotated and then the next rows in succession.

By this action substantially all the coke within the still, practically 85% thereof as 80 has been found in practice, is removed a part at a time.

The coke when removed immediately after the completion of the run as described may be at red heat and upon contact with the air 85 may burst into flame. In such case the flaming coke as it comes from the still is quenched, as by playing a hose thereon.

By the above described mode of operation a great amount of heat existing within 90 the still at the end of a run is removed by actually removing the hot coke itself; and it is the red heat of the coke which under the old and common practice necessitated the cooling of the still, requiring approximately 95 six hours, before men could enter to break up the coke and remove it. When the hot coke has been removed in a relatively short time, say three quarters of an hour, as above described, after removal of the manhole cover 8, the still may be entered and the small remaining amount of coke swept out through the manhole 5, the coke coming freely away from the metal shell of the still. The manhole 5 is of such form that 100 there is no ledge higher than the bottom B over which the frames and coke must be raised or drawn.

The frames, from which all coke has been removed outside the still, are then replaced 110 in the still, the manhole cover 8 replaced and the still recharged for the next run.

By the above described method and apparatus a still of a given size may be cleaned and recharged for the next run in about 115 three to six hours from the time the fire is drawn at the end of the preceding run, whereas with a still of like size and character under the old and common practice the time elapsing has been about twelve hours. 120

Where under the old practice the still is run about sixty hours and is idle about twelve hours, by the method herein described a run of sixty hours is followed by an idle period of approximately only three to six 125 hours, whereby the total time of a run comprising distillation and idle periods is reduced from about 72 hours to about 65 hours. This means that with a given still equipment far more oil can be treated in a 130

given time, with the result that the investment in still structure is far more productive.

What I claim is:

- 5 1. The combination with a horizontal cylindrical oil still having an opening in one end thereof, the lower boundary of said opening being arcuate and coinciding with the arcuate bottom of said still, of manhole structure having an arcuate portion surrounding the lower boundary of said opening, the inner arcuate wall of said manhole structure lying below the inner surface of the arcuate bottom of said still.
- 10 2. The combination with a horizontal cylindrical oil still, of a manhole structure forming a segmental opening whose lower arcuate edge conforms to the curved still bottom throughout substantially the arcuate width of said structure.
- 15 3. Apparatus for removing deposit from an oil still comprising a plurality of members adapted to be laid upon the still bottom, and means interconnecting said members for imparting thereto rotating and longitudinal movements.
- 20 4. Apparatus for removing deposit from an oil still comprising a plurality of rigid frames adapted to be laid upon the still bottom, and flexible connections between said frames connecting them in chain.
- 25 5. Apparatus for removing deposit from an oil still comprising a rigid frame, said frame having a member extending across the same, and flexible connections at the ends of said member.
- 30 6. Apparatus for removing deposit from an oil still comprising a plurality of rectangular rigid frames, and flexible connections at corners of said frames connecting them in chain.
- 35 7. Apparatus for removing deposit from an oil still comprising a plurality of rigid frames, and flexible connections at corners of said frames connecting them in chain.
- 40 8. Apparatus for removing deposit from an oil still comprising a plurality of rigid frames adapted to be laid in transverse rows upon the bottom of the still, and flexible connections between the frames of a row and between said rows.
- 45 9. The combination with an oil still, of a manhole structure having an opening extending to the still bottom, and a plurality of flexibly interconnected members disposed within said still and adapted to be withdrawn horizontally along the still bottom and through said manhole opening.
- 50 10. The combination with a horizontal cylindrical oil still, of a segmental manhole structure extending to the bottom at the end of said still, and a plurality of flexibly interconnected frames disposed within said still and adapted to be withdrawn horizontally through said manhole structure.
- 55 11. The combination with an oil still having an opening whose lower edge coincides with the curved still bottom, of a plurality of flexibly interconnected frames disposed within said still on its bottom and adapted to be withdrawn horizontally along the still bottom through said opening. 70
- 60 12. The combination with a horizontal cylindrical oil still, of a manhole structure forming an opening whose arcuate lower edge coincides substantially with the curved still bottom, and a flange on said manhole structure disposed on the outside of said still bottom and in contact therewith throughout substantially the arcuate width of said structure. 75
- 65 13. The combination with a cylindrical oil still, of a segmental manhole structure whose arcuate portion corresponds substantially with the curved still bottom, and a plurality of flexibly interconnected frames disposed within said still upon its bottom in successive transverse rows and adapted to be withdrawn in succession through said manhole structure. 80 85
- 70 14. The combination with a cylindrical oil still, of a segmental manhole structure whose arcuate portion corresponds substantially with the curved still bottom, and a plurality of transverse rows of frames, means connecting adjacent frames of a row to cause a pull imparted to a frame to exert a twist and pull upon the neighboring frame, and means for connecting the rows of frames in series. 90 95
- 75 15. The combination with an oil still, of a structure forming an opening coinciding substantially with the still bottom, a plurality of frames upon the still bottom, connectors between said frames connecting them in series, each connector connected to such point of a frame that a pull upon said connector rotates said frame and thereafter pulls it in direction for exit from the still. 100 105
- 80 16. The combination with an oil still, of a structure forming an opening coinciding substantially with the still bottom, a plurality of polygonal frames upon the still bottom, and connectors connecting said frames in series, each connector extending from a corner of one frame to a corner of another frame later in the series, said other frame being so disposed that a pull outwardly through said still opening produces rotation followed by longitudinal movement 110 115 120 of said other frame.
- 85 17. The combination with an oil still, of a structure forming an opening coinciding substantially with the still bottom, a plurality of frames disposed in successive transverse rows upon said still bottom, and connectors connecting said frames in series, each connector extending from a corner of one frame to a corner of another frame later in the series, said other frame 125 130

being so disposed that a pull outwardly through said still opening produces rotation followed by longitudinal movement of said other frame.

5 18. The combination with an oil still, of structure forming an opening coinciding substantially with the still bottom, a plurality of polygonal frames upon the still bottom, means connecting said frames in 10 series whereby they may be withdrawn in succession through said opening, each frame having a diagonally extending member, and connectors for connecting said frames in series connected to the ends of 15 said diagonally extending members.

19. The combination with an oil still, of structure forming an opening coinciding substantially with the still bottom, a plurality of rectangular frames upon the still 20 bottom placed with their sides substantially

parallel, and means connecting said frames in chain connected to corners of said frames.

20. The combination with an oil still, of structure forming an opening coinciding substantially with the still bottom, a plurality of rectangular frames disposed in transverse rows upon said still bottom, the sides of said frames being substantially parallel with each other, and means for connecting said frames in series comprising 25 flexible connectors connecting corners of said frames, whereby the frames are pulled in succession from the still and each frame 30 first rotated with respect to the still bottom.

35 In testimony whereof I have hereunto affixed my signature this 4th day of March, 1919.

CHARLES B. BUERGER.
